CLAIM

The ornamental design for an insert for a drawer, as shown and described.

DESCRIPTION

FIG. 1 is a perspective view of an insert for a drawer, with the insert placed in the drawer in open condition

FIG. 2 is a perspective view of the insert for a drawer;

FIG. 3 is a top view of the insert for a drawer;

FIG. 4 is a bottom view of the insert for a drawer;

FIG. 5 is a front view of the insert for a drawer;

FIG. 6 is a one side view of the insert for a drawer;

FIG. 7 is a back side view of the insert for a drawer; and,

FIG. 8 is another side view of the insert for a drawer.

The broken lines shown in the drawings are for illustrative purposes only and form no part of the claimed design.

1 Claim, 5 Drawing Sheets
